UNITED STATES PATENT OFFICE.

ADOLPH STORM AND EDWARD C. O'HAIR, OF THOMPSON, IOWA, ASSIGNORS TO STORM AND O'HAIR COMPANY, A COPARTNERSHIP CONSISTING OF OSCAR W. NELSON AND EDWARD C. O'HAIR, OF THOMPSON, IOWA.

BORING-MACHINE.

1,209,513.

Specification of Letters Patent. Patented Dec. 19, 1916.

Application filed January 5, 1916. Serial No. 70,451.

To all whom it may concern:

Be it known that we, ADOLPH STORM and EDWARD C. O'HAIR, citizens of the United States, residing at Thompson, in the county 5 of Winnebago, State of Iowa, have invented certain new and useful Improvements in Boring-Machines; and we do hereby declare the following to be a full, clear, and exact description of the invention, such as 10 will enable others skilled in the art to which it appertains to make and use the same.

Our invention relates to boring machines of the type adapted for use in reboring the cylinders of explosive engines.

15 It is our purpose to provide a boring machine of the type named in which the parts are capable of rearrangement in a quick and easy manner so that the machine can be utilized in reboring cylinders with non-detachable heads by inverting the cylinder and operating the cutter head downwardly, and also in reboring cylinders with detachable heads by reversing the cutter head and then operating the latter upwardly through 20 the medium of a left hand thread bar.

It is our further purpose to provide a cutter head with which may be detachably associated split lead rings to enable the head to be utilized with facility in cylinders having 30 bores of different diameters.

With the above and other objects in view our invention consists in the details of construction and in the arrangement and combination of parts to be hereinafter more 35 fully described and particularly pointed out in the appended claims.

In describing the invention in detail reference will be had to the accompanying drawings wherein like characters of reference 40 denote corresponding parts in the several views, and in which—

Figure 1 is a vertical section of a fragment of a cylinder of an explosive engine, said cylinder being of the non-detachable 45 head type and the improved boring machine being applied to initiate reboring of the cylinder; Fig. 2, a vertical section through the cutter head of the device; Fig. 3, a view similar to Fig. 2 taken on another plane and 50 showing the lead ring applied to the head; Fig. 4, a plan view of what is shown in Fig. 2; Fig. 5, a vertical section through a fragment of the upper portion of the machine;

and Fig. 6, a view similar to Fig. 1 showing the manner of applying the machine to institute the reboring of a cylinder having a detachable head.

Referring to Figs. 1 to 5 inclusive the invention is shown as comprising a substantially circular head A including sections 10 and 11 detachably secured together by means of lock screws 12. The section 11 is adapted to be correctly positioned with respect to the section 10 for the application of the lock screws 12 by means of studs 13 fixed to the section 10 and engageable in passages 14 formed in the section 11. The sections 10 and 11 are provided centrally with aligned axial passages 14 and 15 respectively, said passages being respectively provided with threads 16 and 17. The outer end of the section 10 is beveled circumferentially as at 18 for a purpose that will presently appear. The section 10 is provided on its inner end with a plurality of radial grooves 19 in each 75 of which is seated a cutter 20 and these cutters are held in place through the medium of the section 11 which latter is clamped against the cutters by the action of the lock screws 12 as will be obvious. Each of the cutters 20 has its inner end provided with a beveled portion 21 adapted to coact with an adjusting element to be presently referred to. Engaged with the threads 16 of the passage 15 is the lower end of a tubular thread bar 22 the upper end of which is suitably squared to receive an operating handle 23 for effecting rotation of the bar. This bar 22 has threaded engagement with a tubular bushing 24 mounted in a central opening 25 of a guide 90 and feed plate 26, said plate 26 resting on the upper end of a tubular guide rest 27 the lower end of which engages with the body of the engine structure. Disposed on the upper side of the feed plate 26 is a feed 95 plate holder 28 provided with a central opening 29 through which the thread bar 22 passes. This feed plate holder 28 is provided with lateral extensions 30 provided respectively with slots 31 through which latter are engaged bolts 32 adapted to be threaded in a convenient threaded opening in the engine body for the purpose of securing the machine in a fixed operative relation to the cylinder to be bored.

Disposed in the bore of the thread bar 22

is a rod 33 the inner end of which projects into the passages 14 and 15 and is provided with a head 34 having threaded engagement with the thread 16 and including a tapered portion 35 coaxing with the beveled inner ends 21 of the cutters 20 so that when the rod 33 is rotated in one direction the head 34 will be moved toward the section 11 and force the cutters 20 outwardly. The end of the rod 33 remote from the head 34 is squared as at 36 for the reception of a suitable wrench for facilitating rotation of the rod 33 to adjust the cutters 20.

When it is desired to re bore a cylinder 15 having a non-detachable head said cylinder is first inverted and the boring machine applied as shown in Fig. 1. When the machine is thus applied it will be obvious that rotation of the thread bar 22 through the 20 medium of the handle 23 will rotate the cutter head and at the same time feed the head downwardly in the cylinder and thus effect the proper boring operation. In order to center the cutter head during initial boring 25 we provide the guide rest 27 and apply a bearing ring 37 around the section 11 which ring bears against the inner wall of the rest 27. We further apply a split lead ring 38 around the beveled portion 18 of the section 30 10. These rings 37 and 38 serve to hold the cutter head centered during the first part of the boring operation under the conditions shown in Fig. 1 until the head has fully entered the cylinder when the ring 37 will be 35 come automatically detached. The lead ring 38 also enables a single cutter head to be utilized in reboring cylinders having bores of different diameters. The ring 37 is also utilized in adjusting the cutters 20 before the 40 boring operation is instituted, the ring being placed around the section 10 in the plane of the cutters and the latter then adjusted until they properly engage the inner face of the ring when the latter is removed after the 45 cutter has been locked by manipulating the screws 12. It will of course be understood that a number of rings 37 and 38 of different sizes are employed in connection with a single boring machine so as to maintain the

utility of the machine under varying conditions of work.

Referring now particularly to Fig. 6 wherein the cylinder to be rebored is of the detachable head type it will be noted that the cutter head is moved upwardly and to effect 55 this said head is reversed and a left hand thread bar 22 employed with its lower end engaged with the threads 16. Under these conditions the cutters 20 are also turned so as to properly present the beveled inner 60 ends 21 to the tapered portion 35 of the head 34.

What is claimed is:—

1. In a boring machine of the class described, a cutter head comprising a pair of sections arranged end to end, locking screws for clamping said sections together, said sections being provided with aligned longitudinal threaded passages, one of said sections having its inner end provided with a plurality of radial grooves, cutters adjustably mounted in said grooves and having beveled inner end portions, a tapered adjusting member threaded in one of said longitudinal passages and coaxing with the beveled 75 inner ends of the cutters to force the latter outwardly when said member is rotated in one direction, and a tubular thread bar engaged in the other longitudinal passage and through the bore of which the adjusting 80 member extends.

2. In a boring machine of the class described the combination of a head having a longitudinally threaded passage therein adapted to receive a thread bar, one of the 85 ends of said head being circumferentially beveled to receive a correspondingly beveled lead ring, and cutters adjustably mounted in said head.

In testimony whereof, we affix our signatures in the presence of witnesses:

ADOLPH STORM.
EDWARD C. O'HAIR.
